HOLDER FOR RAZOR BLADES

Charles William Caldwell, Johannesburg, Transvaal, Union of South Africa

Application May 20, 1944, Serial No. 536,573

1 Claim. (Cl. 30—331)

This invention relates to holders in which a wafer type razor blade is secured to enable the blade to be stropped or used as a knife.

The object of the invention is to provide such a holder which secures the blade firmly in position by a simple clamping action. The invention attains this object by pressing a face of the razor blade against a supporting member having an antislipping surface.

A hand tool adapted to hold a wafer blade for stropping by hand operation is shown in the accompanying drawing in which

Figure I is a perspective view of the holder with the blade clamped therein.

Figure II shows the holder open for receiving or removing the blade.

Figure III is a cross section on III—III Figure I drawn to an enlarged scale.

The holder comprises a fixed clamp jaw 2 and a movable clamp jaw 3 made of sheet metal and lying parallel with one another. The jaw 2 is rigid with a handle 4 and projects from one side thereof; the handle being for instance inserted into a socket 5 formed by curling a long edge of the jaw 2. The jaw 3 is pivoted to jaw 2 at 6 so that it can be swung open, while remaining parallel with jaw 2 and as shown in Figure II, to enable the razor blade 7 to be laid flat on jaw 2.

Jaw 3 is retained in its clamping position, Figure I, by its non-pivoted end 8 being passed under an ear 9 extending from jaw 2. Said jaw 3 is somewhat bowed in edge view and is capable of elastic bending endwise, to ensure that it exerts effective clamping pressure centrally on the razor blade when its end 8 is retained under ear 9. Its edge 10 is rounded outward sufficient to ensure its sliding smoothly over the razor blade while it is being swung to its clamping position.

The construction described provides a desirably thin holder of very simple form, distinguished by having no structural parts for positively securing or positioning the razor blade, which can accordingly be produced at low cost. However, such materials, e. g. sheet metal, as are suitable for the manufacture of the jaws are smooth and hard, and if the tangential frictional adhesion between the smooth and hard jaw surfaces and the similarly smooth and hard faces of the razor blade were relied upon to hold the blade against move-

ment in its own plane, the result would be unsatisfactory owing to the low co-efficient of friction between said surfaces.

Accordingly a piece of double faced friction tape 11 is stuck, by its adhesive lower face, to the inner face of jaw 2, and presents an exposed adhesive face 12 on which the blade is laid. The clamping pressure perpendicular to the blade faces, without being of more than moderate magnitude, causes the blade to embed itself slightly in the surface 12 and the blade face to adhere to said surface thereby setting up strong tangential frictional resistance to blade movement. This resistance is effective both while the jaw 3 is being closed and while the blade is being stropped or used. On the other hand, upon the clamping pressure being removed by opening the jaw 3, there is no difficulty in lifting the blade 7 perpendicularly off the surface 12.

The socket 5 provides a shoulder 13 against which the back edge 14, for the time being, of the razor blade may be abutted, ensuring that each time a blade of standard width is housed in the holder, the projection of its outer edge 15 will always be uniform.

The socket 5, when rested on the strop, ensures a constant elevation of the back edge 14 of the blade and in combination with the uniform projection of edge 15 ensures that the bevel angle at which the razor edge is presented to the strop, will also be constant.

The piece of tape 11 is continued over the shoulder 13, to protect the back blade edge 14 from damage by actual contact with the metal of said shoulder.

I claim:

A razor blade holder comprising a handle, a jaw fixed to said handle and providing an antislipping surface for a razor blade to rest upon and also providing a shoulder for one edge of the razor blade to rest against; a movable jaw pivoted to the fixed jaw to swing into and out of a position in which it clamps the razor blade against the anti-slipping surface; and means, on the fixed jaw, for so holding said movable jaw in its clamping position that said movable jaw, which is initially curved convexly to the fixed jaw, is elastically flattened against the inserted razor blade.

CHARLES WILLIAM CALDWELL.
